UNITED STATES PATENT OFFICE.

JACOB WOLF, OF STILLWATER, MINNESOTA.

CHURN.

SPECIFICATION forming part of Letters Patent No. 351,555, dated October 26, 1886.

Application filed July 21, 1886. Serial No. 208,602. (No model.)

To all whom it may concern:

Be it known that I, JACOB WOLF, a citizen of the United States, residing at Stillwater, in the State of Minnesota, have invented certain new and useful Improvements in Churns, of which the following is a specification, reference being had therein to the accompanying drawings.

My invention relates to churns of rotary character; and its object, more particularly, is to provide a dasher-frame so constructed and arranged with the box that it may readily be removed for cleansing and other purposes, and as readily replaced when desired for use, as will be hereinafter more particularly set forth.

In the accompanying drawings, making part of this specification, Figure 1 represents a perspective view, with one side of the box removed, its top raised, and other portions as seen in section. Figs. 2 and 3 are detached sectional views of the mode of securing the frame in the box.

In the figures, A represents a churn body or box, which may be made square or rectangular and mounted upon a frame, B B, between two standards, as C. These standards, as is usual in this class of churning, have bearings upon their upper ends, in which trunnions upon the sides of the box rest and play, as shown in dotted lines in Fig. 1 of the drawings. A handle connected to one of the trunnions serves to give a rotary motion to the box. The box A has a top, E, upon the under side of which is secured a packing of rubber tubing, F, which, fitting upon the upper edges of the box, makes an air-tight joint. This top is held in place by the bails G H at each end.

I will now refer to the invention to be claimed.

D represents the dasher-frame, which consists of four cross-bars, d d and d' d', and their connecting dasher rods or blades e e and m m, as represented, forming a stationary breaking-frame in the box, revolving with said box, but

not independent of it. At one side the ends of the bars d d' are rounded or tapered, as shown, in order to enter the recesses a a in one side of the churn-body when the frame D is in position. To place the frame D in the churn-box, the tapered ends of the bars d d', above mentioned, are first inserted in the recesses a a at an angle to the side of the churn-box, as shown in Fig. 3 of the drawings, and the frame then swung down into place. When the frame D is in its place in the box, the ends of the cross-bars d d and d' d' are intended to fit snugly in the ends and bottom of said box. Upon one of the bars d is pivoted a button, n. This button is raised when the frame is to be removed, but is turned down so as to fit tightly against one side of the box when the frame is to be held in place. By this construction and arrangement the frame can be removed in a moment or replaced as quickly, as the necessities of the case may demand.

Having thus fully described my invention, what I claim as new, and desire to secure by Letters Patent, is—

In combination with the churn body or box mounted upon a suitable frame to enable it to be revolved, the churning-frame consisting of bars crossing at or near their center and connected together by dasher blades and rods, the ends of the horizontal bars at one side being tapered or rounded in order to enter recesses in the interior of the churn-body, and one of the vertical bars having pivoted to it near its top a locking-button adapted to bear against the inside of the churn-body and securely hold the frame therein, substantially as specified.

In testimony whereof I affix my signature in presence of two witnesses.

JACOB WOLF.
